UNITED STATES PATENT OFFICE.

LAUREN S. BEARDSLEY, OF NAUGATUCK, CONNECTICUT.

DESIGN FOR AN INSULATOR-HOLDER.

SPECIFICATION forming part of Design No. 24,190, dated April 9, 1895.

Application filed January 12, 1895. Serial No. 534,713. Term of patent 7 years.

To all whom it may concern:

Be it known that I, LAUREN S. BEARDSLEY, a citizen of the United States, residing at Naugatuck, in the county of New Haven and State of Connecticut, have invented and produced a new and original Design for Insulator Holders, of which the following is a specification, reference being had to the accompanying drawings, forming part of this specification, in which—

Figure 1 is an elevation of an insulator-holder made in accordance with my new design. Fig. 2 is a transverse section on the line $x-x$ of Fig. 1.

The distinguishing feature of my design is the shape of the stem or body A of the holder,

between the end portions a and B; the said part of the holder consisting of the pillars a' surrounding a central opening a³ and separated by the longitudinal slots a². 20

What I claim is—

The design for an insulator holder substantially as shown and described.

In testimony whereof I have hereunto affixed my signature, at Naugatuck, in the county of New Haven and State of Connecticut, this 31st day of December, 1894.

LAUREN S. BEARDSLEY.

Witnesses:

HENRY P. McCARTHY,
FRANK J. CONRAN.
